UNITED STATES PATENT OFFICE.

LLOYD V. LEWIS, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING SYSTEM.

1,407,287.

Specification of Letters Patent. Patented Feb. 21, 1922.

Application filed January 9, 1920. Serial No. 350,322.

To all whom it may concern:

Be it known that I, LLOYD V. LEWIS, a citizen of the United States, residing at Wilkinsburg, in the county of Allegheny and State of Pennsylvania, have invented certain new and useful Improvements in Railway-Traffic-Controlling Systems, of which the following is a specification.

My invention relates to railway traffic controlling systems, and particularly to systems of the type wherein alternating current is supplied to the trackway for the control of suitable governing apparatus carried by the cars or trains.

15 In one system of the type mentioned, it has been proposed to employ the usual track circuit current, that is, the current which energizes the track relays, as one of the currents for controlling the train-carried 20 governing apparatus, the train governing apparatus being controlled by this current through the medium of receiving appliances at the front end of the train. When this is done, it is obvious that the source of 25 track circuit current must always be connected across the track rails ahead of a train.

In the case of a double track railroad 30 wherein traffic on each track normally moves in one direction only, this requirement is readily met in so far as movements in the normal direction are concerned, because the source of track circuit current for each section of track is then connected across the 35 rails at the exit end of the section in accordance with standard practice in automatic block signalling. On roads of this kind, however, it is sometimes necessary for trains to move in opposition to the normal 40 direction of traffic, and in such instances with only the trackway apparatus thus far mentioned the train would not receive track circuit current. One feature of my invention is the provision of means located in the track- 45 way for connecting an auxiliary source of track circuit across the rails of each section at what is normally the entrance end of the section, to permit train movements in opposition to the normal direction of traffic.

50 In systems of this type it has also been proposed to supply a second, or "line circuit current", to the trackway which current coacts with the track circuit current to

control the train governing apparatus. This line circuit current is supplied to only 55 the rear portion of each section when the section next in advance is occupied, and so it follows that when a train moving against the normal direction of traffic enters a section it will not receive line circuit current 60 until the rear end of the train has passed out of the adjacent section. Another feature of my invention is the provision of means for at times supplying line circuit current to each section throughout the entire 65 section, regardless of conditions in any other section, so that a train moving against the normal direction of traffic may pass through the section without restriction.

I will describe two forms of trackway 70 apparatus embodying my invention, and will then point out the novel features thereof in claims.

In the accompanying drawings, Fig. 1 is 75 a diagrammatic view showing one track of a double track railway equipped with trackway apparatus embodying my invention, and Fig. 2 is a view showing a modification of the trackway apparatus also embodying my invention. 80

Referring first to Fig. 1, the reference characters 2 and 2^a designate the two traffic rails of a railway track over which traffic normally moves only in the direction indicated by the arrow. These rails are divided 85 by insulated joints 3 into a plurality of successive sections, of which only two complete sections A—B and B—C are shown in the drawing.

Each track section is provided with a track 90 circuit comprising as usual the track rails of the section, a source of alternating current connected across the rails at the exit end of the section, and a track relay connected across the rails at the entrance end of the 95 section. As here shown, the source of current for each track circuit is a transformer designated by the reference character E with an exponent corresponding to the location, the secondary of which transformer is connected across the rails through a reactance 100 10 and the primary of which is constantly connected through a pole-changer P with the secondary of a transformer designated D with an exponent corresponding to the location. The primary of each transformer D is 105

connected with a transmission line F which is supplied with alternating signaling current by a generator G. The track relay for each section is designated by the reference character T with an exponent corresponding to the location. Each of these track relays is of the induction motor type comprising two stator windings 4 and 5 and a rotor 6, which rotor controls three contacts 7, 8 and 9. The stator winding 4 is normally connected with the track rails, as hereinafter explained, whereas the winding 5 is constantly supplied with alternating current from the secondary of the adjacent transformer D. It follows that contacts 7, 8 and 9 of each relay will be swung to the right or to the left according as current of one relative polarity or the other is supplied from the track circuit to the stator winding 4, and that these contacts will rest in the vertical position when the supply of current to the winding 4 ceases. The relay contacts 7, 8 and 9 are swung to the right when the track circuit is of one relative polarity, which I will call normal, and to the left when the track circuit current is of the other relative polarity, which I will term reverse.

Located adjacent the entrance end of each section is a roadside signal designated by the reference character S with an exponent corresponding to the location. Each of these signals, as here shown, is of the semaphore type adapted to indicate "Stop," "Caution" or "Proceed," according as the semaphore is in the horizontal, the inclined, or the vertical position. Each signal is controlled by the track relay for the corresponding block through the medium of a caution indication circuit and a proceed indication circuit. Considering signal S^B, for example, the caution indication circuit (which is open in the drawing) is from the secondary of transformer D^B, through wires 11 and 12, left-hand point of contact 7 of track relay T^B, wire 13, operating mechanism of signal S^B, wire 14, left-hand point of contact 8 of track relay T^B, and wires 15 and 16 to the secondary of transformer T^B. The proceed indication circuit is from the secondary of transformer T^B, through wires 11 and 12, right-hand point of contact 7 of track relay T^B, operating mechanism of signal S^B, wire 14, right-hand point of contact 8, and wires 15 and 16 to the secondary of transformer D^B. It will be seen, therefore, that signal S^B indicates caution or proceed according as track relay T^B is energized in the reverse or normal direction.

The pole-changer P which is included in each track circuit is operated by the signal S for the section next in advance in such manner that the polarity of the current supplied to the track circuit is normal when the signal indicates proceed or caution, and reverse when the signal indicates stop. It will

be seen, therefore, that track circuit current of reverse polarity is supplied to the rails of the section in the rear of an occupied section, but that track circuit current of normal polarity is supplied to the rails of the section in the rear of an unoccupied section.

I have said that winding 4 of each track relay T is normally connected with the rails of the corresponding section at the entrance end of the section. Means are provided, however, for at times disconnecting this relay winding from the track rails and connecting a source of alternating current with the rails in its place, and this means I will now describe.

Located adjacent the entrance end of each section is a traffic direction relay, designated H with an exponent corresponding to the location. Each of these relays is employed to connect the rails at the entrance end of the corresponding section with winding 4 of the track relay when the traffic direction relay is de-energized, and with the secondary of the adjacent track transformer E when the traffic direction relay is energized. Considering section B-C, for example, when the traffic direction relay H^B is de-energized, winding 4 of relay T^B is connected with the rails of the section, the circuit being from the lower rail 2^a, through wire 18, back point of contact 19 of relay H^B, wire 20, winding 4 of relay T^B, wire 23, back point of contact 22 of relay H^B, and wire 21 to the upper rail 2. When relay H^B is energized, however, winding 4 of track relay T^B is disconnected from the rails of section B-C and the secondary of transformer E^B is connected with these rails, the circuit being from the lower rail 2^a, through wire 18, front point of contact 19 of relay H^B, wire 26, secondary of transformer E^B, reactance 25, wire 24, front point of contact 22 of relay H^B, and wire 21 to the upper rail 2. The function of each of the other traffic direction relays H is the same as that of relay H^B.

Each traffic direction relay H is connected across a pair of wires 30 and 31 extending along the stretch of track, and these wires are at times connected with the secondary of a transformer 29, the primary of which is constantly supplied with alternating current from the transmission mains F. The supply of current to the line wires 30 and 31 is controlled by a circuit controller K which is located in a tower J. This circuit controller K comprises a manually operable lever 32 which operates two contacts 27 and 28. When the lever 32 is in the position shown, which I will term the normal position, contacts 27 and 28 are open, so that the traffic direction relays H are de-energized, but when handle 32 is swung to the right, to what I will term its reverse position, the contacts operated thereby are

closed, so that relays H^A , H^B , and H^C become energized.

As long as traffic is to proceed along the rail way track in the normal direction, that is, in the direction indicated by the arrow, circuit controller K is left in the position shown, so that the traffic direction relays are de-energized. The operation of the system is then in accordance with usual practice, so that no detailed explanation is required. Suffice it to say, that at such times a source of alternating current is connected across the rails of each section at the exit end of the section, and a track relay is connected across the rails at the entrance end of each section. When a train movement in the direction opposite to normal is desired, circuit controller K is reversed, whereupon the traffic direction relays H become energized, so that a source of alternating current is connected across the rails of each section at what is normally the entrance end of the section.

Each track section is provided with two line circuits, one of which extends from the entrance end to an intermediate point 34 and the other of which extends from the intermediate point 34 to the exit end of the section, these two line circuits being termed the rear and the forward circuits respectively. As shown in Fig. 1, each line circuit includes the two track rails in multiple, the current being supplied to the rails of each section through resistances 33, 34 and 35 which are connected across the rails at the entrance end, the intermediate point, and the exit end of the section, respectively. Again considering section B-C, the rear line circuit for this section is from secondary 36 of a transformer M^B , through wire 37, contact 9 of track relay T^B , wire 38 to the middle point of resistance 33, thence through the two track rails 2 and 2^a in multiple to resistance 34, and from the middle point of this resistance, through wires 39 and 40 to the secondary 36 of transformer M^B . The primary of transformer M^B is constantly supplied with current from the secondary of transformer D, the primary of which, as has been said, is connected with the transmission mains F. Track relay contact 9 is closed only when the relay is de-energized, and, consequently, current is supplied to the rear line circuit only when section B-C is occupied by a car or train, or when track relay T^B is disconnected from the rails by traffic direction relay H^B . The forward line circuit for section B-C is from secondary 41 of transformer M^C , through wires 42 and 39, to the middle point of resistance 34, thence through the two track rails in multiple to resistance 35, and from the middle point of this resistance through wires 43 and 44, contact Q^c, and wires 45 and 46 to second-

ary 41 of transformer M^C . Contact Q^c is operated by signal S^c in such manner that this contact is closed when the signal indicates proceed or caution, but open when the signal indicates stop. It will be seen, therefore, that so far as the line circuit just traced is concerned, current is supplied thereto only when signal S^c indicates proceed or caution. This circuit is provided with a branch, however, around contact Q^c, which branch passes from wire 43, through wire 47, contact 48 of traffic direction relay H^C , and wire 49 to wire 46. It follows that when traffic direction relay H^C is energized, current is supplied to the forward line circuit, regardless of the position of signal S^c, that is, regardless of traffic conditions extraneous to section B-C.

Before explaining the operation of the system as a whole it should be pointed out that the trackway apparatus here shown is intended for co-operation with train-carried governing apparatus which operates in the following manner: When the train is on a portion of track which is supplied with track circuit current of normal polarity and also with line circuit current, the governing apparatus permits the train to travel at high speed, such as 65 miles per hour. When the portion of track occupied by the train is supplied with track circuit current of reverse polarity and also with line circuit current, the governing apparatus prevents the train from proceeding at more than an intermediate speed, such as 35 miles per hour; but when the train enters a portion of track from which the supply of either track circuit or line circuit current is discontinued, the governing apparatus prevents the train from proceeding at more than a low speed, such as 10 miles per hour. One form of governing apparatus which will co-operate in this manner with the trackway apparatus here shown, is illustrated and described in an application filed by me in the United States Patent Office on Nov. 1, 1918, Serial No. 263607, for railway traffic controlling systems.

The operation of the entire apparatus is as follows:

I will first assume that circuit controller K is in the position shown, so that traffic direction relays H are de-energized, and I will also assume that the stretch of track shown in the drawing is unoccupied and that a train moving in the direction indicated by the arrow enters the stretch. As this train enters section A-B, it de-energizes track relay T^A , so that contacts 7, 8 and 9 move to their intermediate positions. The opening of contacts 7 and 8, of course, causes signal S^A to move to the stop position. The movement of contact 9 to its intermediate position closes the rear line circuit for section A-B, so that line circuit current is supplied to the

rails of this section between resistances 33 and 34. Inasmuch as signal S^B is in the proceed position, track circuit current of normal polarity is supplied to the rails of section 5 A-B from transformer E^B , and line circuit current is supplied to the rails of this section between resistances 34 and 35, that is, to the forward line circuit for the section. It follows, therefore, that the train can proceed 10 through section A-B at 65 miles per hour or less. The operation of the apparatus in section B-C as the train passes therethrough is the same as that of the apparatus in section A-B, and hence it will be understood with- 15 out further explanation.

I will now assume that while the first train is in section B-C, a second train enters section A-B. Signal S^B is then at stop, so that track circuit current of reverse polarity is 20 supplied to the rails of section A-B. Contact Q^B operated by signal S^B is open, so that line circuit current is not supplied to section A-B between resistances 34 and 35. As the second train passes the point A, it will receive 25 line circuit current and it will also receive track circuit current of reverse polarity, so that this train will incur a brake application if it exceeds a speed of 35 miles per hour while between resistances 33 and 34. After 30 passing resistance 34, the train will cease to receive line circuit current, and, consequently, it will incur a brake application if it exceeds 10 miles per hour. If this second train passes signal S^B while the latter is still at stop, it 35 will fail to receive track circuit current, because such current is shunted by the wheels and axles of the first train, and, consequently, the second train will still be compelled to proceed at a speed not exceeding 10 miles 40 per hour.

I will now assume that, owing to an emergency condition, it is necessary for a train to pass over the stretch of track shown in the drawing in the direction opposite to that indicated by the arrow. The operator in tower J then swings circuit controller K to the reverse position, thereby energizing all of the traffic direction relays H. Each of these relays then disconnects winding 4 of the adjacent track relay from the rails of its track section and connects the adjacent transformer E with the rails in place of such winding. The track relays thus become de-energized, so that the signals S move to the stop position. 45 The polarity of the current supplied to the left hand end of each section is then normal. Each relay H also closes the forward line circuit for the section to the left of the relay regardless of traffic conditions extraneous to 50 the section. It follows that a train equipped with apparatus such as that described hereinbefore can then proceed along the track in the direction opposite to that indicated by the arrow at a speed of 65 miles per hour or less, 55 although, of course, such train will have no

protection either by the roadside signals or by the controlling currents received from the track rails. When it is desired to restore the apparatus to the condition corresponding to the normal direction of traffic, circuit controller K is returned to its normal position, thereby de-energizing all of the traffic direction relays H. Each of these relays then disconnects the adjacent transformer E from the rails of the section to the right and connects 70 the adjacent track relay T with the rails of this section. Each signal S then returns to the proceed position, so that the apparatus is again in the condition in which it is shown in the drawing. 75

Referring now to Fig. 2, the apparatus shown herein is the same as that shown in Fig. 1, except as follows:

The main difference between the two views is that in Fig. 2 the line circuits include 85 auxiliary conductors 54 and 54^a located in the trackway instead of the two track rails as in Fig. 1. These line circuits in Fig. 2 are supplied with current by a secondary 50 on each transformer D. Considering section 90 B-C, for example, the forward line circuit is from secondary 50 of transformer D^c, through wire 51, wire 52, contact Q^c, wires 95 53 and 61, auxiliary conductor 54, wire 55, and common wire 0 to secondary 50 of transformer D^c. This circuit is provided with a branch around contact Q^c, which branch is from wire 51, through contact 48 of traffic direction relay H^c and wire 58 to wire 61. The rear line circuit for section B-C is 100 from secondary 50 of transformer D^c, through wire 56, auxiliary conductor 54^a, and common wire 0 to the secondary 50 of transformer D^c.

It will be seen that current is always supplied to the rear line circuit, and that when traffic is in the normal direction the supply of current to the forward line circuit is governed by signal S^c for the block next in advance. When traffic is reversed, however, 110 that is, when relays H are energized, current is supplied to the forward line circuit regardless of traffic conditions extraneous to the section.

The apparatus for supplying track circuit 115 current to the rails of each section is the same as in Fig. 1, except that the circuit for the primary of each transformer E is taken through pole-changing contacts 59 and 60 of the adjacent traffic direction relay H. (See 120 relay H^a.)

In Fig. 2 the traffic direction relays H are connected in series instead of in multiple as in Fig. 1. The circuit for these relays, when circuit controller K is reversed, is from the 125 secondary of transformer 29, through contact 28, wire 30, relay H^c, wire 30^a, relay H^b, wire 30^b, relay H^a, wire 31 and contact 27 to the secondary of transformer 29.

The operation of the apparatus shown in 130

Fig. 2 is substantially the same as that of the apparatus shown in Fig. 1, so that a detailed explanation with respect to Fig. 2 is not necessary.

5. Although I have herein shown and described only two forms of trackway apparatus embodying my invention, it is understood that various changes and modifications may be made therein within the scope of the 10 appended claims without departing from the spirit and scope of my invention.

Having thus described my invention, what I claim is:

1. In combination, a section of railway 15 track over which traffic normally moves in one direction only, a source of alternating current connected across the rails at the exit end of said section, a track relay normally connected across said rails at the entrance 20 end of said section, a signal for the section controlled by said relay, and means for at times disconnecting said relay from the rails and connecting a source of alternating current across the rails at the entrance end of 25 the section.

2. In combination, a section of railway track over which traffic normally moves in one direction only, a source of alternating current connected across said rails at the exit 30 end of said section for co-operation with trains moving in said normal direction, and means for at times connecting a source of alternating current across the rails at the entrance end of said section to permit a train 35 movement over the section in opposition to the normal direction of traffic.

3. In combination, a section of railway track over which traffic normally moves in one direction only, a source of alternating 40 current connected across the rails at the exit end of said section, a track relay and a second source of alternating current located adjacent the entrance end of said section, a signal for the section controlled by said 45 track relay, and a traffic direction relay for connecting said track relay or said second source of alternating current across the rails.

4. In combination, a section of railway track over which traffic normally moves in 50 one direction only, a source of alternating current connected across the rails at the exit end of said section, a track relay and a second source of alternating current located adjacent the entrance end of said section, a signal for the section controlled by said track relay, a traffic direction relay for connecting said track relay or said second source of alternating current across the rails, and manually operable means for governing said traffic controlling relay.

5. In combination, a section of railway track over which traffic normally moves in one direction only, a source of alternating current connected across the rails at the exit 65 end of said section, a track relay normally

connected across said rails at the entrance end of the section, a signal controlled by said relay, a second source of alternating current adjacent the entrance end of the section, and manually controlled means for disconnecting 70 said relay from the rails and connecting said second source of alternating current with the rails at the entrance end of the section to permit a train movement over said section in opposition to the normal direction of traffic. 75

6. In combination, a section of railway track over which traffic normally moves in one direction only, a source of alternating current connected across the rails at the exit end of said section, a second source of alternating current adjacent the entrance end of said section, and manually controlled means for connecting said second source across the rails at the entrance end of the section to permit a train movement over said section in opposition to the normal direction of traffic. 80

7. In combination, a section of railway track over which traffic normally moves in one direction only, a source of alternating current connected across the rails at the exit 90 end of said section for co-operation with trains moving in said normal direction, a second source of alternating current located adjacent the entrance end of said section, and a traffic direction relay for at times connecting said second source of current across the rails at the entrance end of the section to permit a train movement over the section in opposition to said normal direction of traffic. 95

8. In combination, a section of railway 100 track over which traffic normally moves in one direction only, a source of alternating current connected across the rails at the exit end of said section, a second source of alternating current located adjacent the entrance 105 end of said section, a traffic direction relay for at times connecting said second source of current across the rails at the entrance end of the section, and manually controlled means for governing said traffic direction 110 relay.

9. In combination, a stretch of railway track over which traffic normally moves in one direction only, said stretch being divided into a plurality of successive sections, a 115 source of alternating current connected across the track rails of each section at the exit end of the section, a track relay normally connected across the rails of each section at the entrance end of the section, means for each section for at times disconnecting the track relay and connecting the source of alternating current with the track rails at the entrance end of the section, and signals for the sections controlled by said track relays. 120

10. In combination, a stretch of railway traffic over which traffic normally moves in one direction only, said stretch being divided into a plurality of successive sections, a source of alternating current connected

- across the rails of each section at the exit end of the section, a track relay normally connected across the rails at the entrance end of each section, signals for the sections controlled by said track relays, and means controlled from a central point for disconnecting the track relay for each section from the rails thereof and connecting a source of alternating current across the rails of each section at the entrance end of the section.
11. In combination, a stretch of railway track over which traffic moves in one direction only, a source of alternating current connected across the rails of each section at the exit end of the section, a traffic direction relay for each section for connecting a source of alternating current across the rails at the entrance end of the section, and means for controlling all of said traffic direction relays from a central point.
12. In combination, a stretch of railway track over which traffic normally moves in one direction, said stretch being divided into a plurality of successive sections, a source of alternating current connected across the rails of each section at the exit end of the section, a track relay normally connected across the rails of each section adjacent the entrance end of the section, signals for the sections controlled by said track relays, a traffic direction relay for each section for disconnecting the track relay for such section from the rails thereof and connecting a source of alternating current across said rails at the entrance end of the section, and means for controlling all of said traffic direction relays from a central point.
13. In combination, a section of railway track over which traffic normally moves in one direction only, a line circuit for said section extending from the entrance end of the section to an intermediate point in the section and including a source of alternating current, a second line circuit extending from said intermediate point to the exit end of the section, means controlled by traffic conditions in advance of said section for supplying current to said second line circuit, and means for at times supplying alternating current to said second line circuit regardless of traffic conditions extraneous to the section.
14. In combination, a section of railway track over which traffic normally moves in one direction only, a line circuit including the two track rails in multiple from the entrance end of the section to an intermediate point in the section, means for supplying current to said circuit, a second line circuit including the two track rails in multiple from said intermediate point to the exit end of the section, means controlled by traffic conditions in advance of said section for supplying current to said second line circuit, and means for at times supplying
- current to said second line circuit regardless of traffic conditions extraneous to said section.
15. In combination, a section of railway track over which traffic normally moves in one direction only, a line circuit extending from the entrance end of the section to an intermediate point in the section and including a source of alternating current, a second line circuit extending from said intermediate point to the exit end of the section, means controlled by traffic conditions in advance of said section for supplying alternating current to said second line circuit, a traffic direction relay, and means controlled by said relay for removing said last-mentioned means from control by traffic conditions in advance of the section.
16. In combination, a section of railway track over which traffic normally moves in one direction only, means for supplying line circuit current to the two rails of said section in multiple from the entrance end to an intermediate point in the section or from the entrance end to the exit end according to traffic conditions in advance of the section, and means for at times removing said means from control by traffic conditions in advance of the section and supplying line circuit current to the rails throughout the length of the section.
17. In combination, a stretch of railway track over which traffic normally moves in one direction only, said stretch being divided into a plurality of successive sections, a signal for each section, a line circuit for each section extending from the entrance end of the section to an intermediate point in the section and including a source of alternating current, a second line circuit for each section extending from said intermediate point to the exit end of the section, means for each section controlled by the signal for the section next in advance for supplying alternating current to said second line circuit when said signal indicates proceed but not when it indicates stop, and means for each section for at times removing said last-mentioned means from control by the signal for the section in advance.
18. In combination, a stretch of railway track over which traffic normally moves in one direction only, said stretch being divided into a plurality of successive sections, a signal for each section, a line circuit for each section extending from the entrance end of the section to an intermediate point in the section and including a source of alternating current, a second line circuit for each section extending from said intermediate point to the exit end of the section, means for each section controlled by the signal for the section next in advance for supplying alternating current to said second line circuit when said signal indicates proceed but not when

- it indicates stop, a traffic direction relay for each section, means controlled by each traffic direction relay for removing said last-mentioned means from control by the signal for the section next in advance, and means for controlling said traffic direction relays from a central point.
19. In combination, a stretch of railway track over which traffic normally moves in one direction only, said stretch being divided into a plurality of successive sections, a signal for each section, a line circuit for each section extending from the entrance end of the section to an intermediate point in the section and including a source of alternating current, a second line circuit for each section extending from said intermediate point to the exit end of the section and including a contact operated by the signal for the section next in advance which contact is closed when the signal indicates proceed but not when the signal indicates stop, a branch for said second line circuit for each section around said signal-operated contact, and means located at a central point for closing the branch for the second line circuit for each section.
20. In combination, a section of railway track over which traffic normally moves in one direction only, a source of alternating current connected with the track rails adjacent the exit end of the section, a second source of alternating current adjacent the entrance end of the section, a track relay normally connected with the rails adjacent the entrance end of the section, a signal for said section controlled by said track relay, means controlled by traffic conditions in advance of said section for supplying line circuit current to the two track rails in multiple from the entrance end of the section to an intermediate point in the section or from the entrance end to the exit end of the section; and means for at times disconnecting said track relay from the rails and connecting said second source of current with the rails adjacent the entrance end of the section, and supplying line circuit current to the two track rails in multiple throughout the entire section regardless of traffic conditions in advance of the section.
21. In combination, a section of railway track over which traffic normally moves in one direction only, a source of alternating current connected across the rails adjacent the exit end of said section; a second source of alternating current located adjacent the entrance end of the section, a track relay normally connected across the rails adjacent the entrance end of the section, a signal for said section controlled by said track relay; a line circuit for said section extending from the entrance end to an intermediate point in the section and including a source of alternating current, a second line circuit extending from said intermediate point to the exit end of the section, means controlled by traffic conditions in advance of said section for supplying alternating current to said second line circuit, and means for at times disconnecting said track relay from the rails of the section, connecting said second source of current across the rails at the entrance end of the section, and supplying alternating current to said second line circuit regardless of traffic conditions extraneous to the section.
22. In combination, a stretch of railway track over which traffic normally moves in one direction only, said stretch being divided into a plurality of successive sections, a line circuit for each section extending from the entrance end of the section to an intermediate point in the section and including a source of alternating current, a second line circuit for each section extending from said intermediate point to the exit end of the section, means for each section normally controlled by traffic conditions in advance of the section for supplying alternating current to said second line circuit, a traffic direction relay for each section for removing said last-mentioned means from control by traffic conditions in advance, and means for controlling all of said traffic direction relays from a central point.
23. In combination, a section of railway track over which traffic normally moves in one direction only, means normally controlled by traffic conditions in advance of said section for supplying line circuit current to the section for co-operation with trains moving in normal direction over the section, and means for at times supplying line circuit current to said section regardless of traffic conditions extraneous to the section to permit a train movement in opposition to the normal direction of traffic.
24. In combination, a section of railway track over which traffic normally moves in one direction only, means normally controlled by traffic conditions in advance of said section for supplying line circuit current to the section for co-operation with trains moving in normal direction over the section, and manually controlled means for at times supplying line circuit current to said section regardless of traffic conditions extraneous to the section to permit a train movement thereover in opposition to the normal direction of traffic.
- In testimony whereof I affix my signature in presence of two witnesses.
- LLOYD V. LEWIS.
- Witnesses:
- A. HERMAN WEGNER,
E. P. CRUM.
